(57) **CLAIM**

The ornamental design for a mounting bracket, as shown and described.

DESCRIPTION

FIG. 1 is an isometric view, taken slightly from above, of a mounting bracket showing my new design;

FIG. 2 is a top plan view thereof;

FIG. 3 is a top plan view of Detail 3 of the mounting bracket shown in FIG. 2; and,

FIG. 4 is a bottom view thereof.

The broken lines in FIGS. 1-4 are included for the purpose of showing features on the mounting bracket that form no part of the claimed design.
